Robert J. Peterson,

BY
Joseph L. Levy
ATTORNEY

UNITED STATES PATENT OFFICE.

ROBERT J. PETERSON, OF MOUNT VERNON, NEW YORK.

DESIGN FOR FABRIC.

SPECIFICATION forming part of Design No. 29,606, dated November 1, 1898.

Application filed May 23, 1898. Serial No. 681,516. Term of patent 14 years.

To all whom it may concern:

Be it known that I, ROBERT J. PETERSON, a citizen of the United States, residing at Mount Vernon, county of Westchester, State 5 of New York, have invented and produced a certain new and original Design for a Fabric or Similar Article, of which the following is a specification.

My invention resides in the design for a fabric or similar article.

The design consists substantially in a successive series of groups of straight-sided and parallel bars 1, 2, and 3, printed or woven in the fabric, the bars extending across the fabric diagonally to the direction of the length 5 of the piece, said bars alternating in color or

shade, each bar contrasting in shade with the other.

The groups or series of three differentiated or contrasted bars are disposed over the face 20 of the piece of fabric diagonally to the direction of its length or its sides or selvage.

Having described my invention, I claim—

The design for a fabric or similar article, substantially as shown and described. 25

Signed in the city, county, and State of New York this 20th day of May, 1898.

ROBT. J. PETERSON.
